Primary Examiner — Elizabeth J Oswecki*(74) Attorney, Agent, or Firm* — Pearne & Gordon LLP**CLAIM**

The ornamental design for a substrate retaining ring, as shown and described.

DESCRIPTION

FIG. 1 is a top perspective view of a substrate retaining ring, showing our new design;

FIG. 2 is a bottom perspective view thereof;

FIG. 3 is a top plan view thereof;

FIG. 4 is a bottom plan view thereof;

FIG. 5 is a side view thereof, with the ring being radially symmetrical about a vertical axis;

FIG. 6 is a cross sectional view taken along line 6-6 in FIG. 3;

FIG. 7 is a cross sectional view taken along line 7-7 in FIG. 3; and,

FIG. 8 is a cross sectional view taken along line 8-8 in FIG. 3.

1 Claim, 4 Drawing Sheets---
